UNITED STATES PATENT OFFICE

151,015

DESIGN FOR A PORTABLE ELECTRIC
HEATER

Harry L. Stiles, Chicago, Ill., assignor to Chicago
Electric Manufacturing Company, Chicago, Ill.,
a corporation of Illinois

Application October 10, 1947, Serial No. 141,856

Term of patent 14 years

(Cl. D81—19)

To all whom it may concern:

Be it known that I, Harry L. Stiles, a citizen of the United States, residing in Chicago, Cook County, State of Illinois, have invented a new, original, and ornamental Design for Portable Electric Heater, of which the following is a specification, reference being had to the accompanying drawing, forming a part thereof.

Fig. 1 is a front elevational view of a portable electric heater, showing my new design;

Fig. 2 is a side view of the heater; and

Fig. 3 is a rear view of the heater.

I claim:

The ornamental design for a portable electric heater, as shown.

HARRY L. STILES.
